UNITED STATES PATENT OFFICE

127,695

DESIGN FOR A STAIR TREAD

Thomas J. Lewis, Ridgefield Park, N. J., assignor
to Borden Metal Products Company, Elizabeth,
N. J., a corporation of New Jersey

Application January 10, 1941, Serial No. 97,966

Term of patent 7 years

To all whom it may concern:

Be it known that I, Thomas J. Lewis, a citizen
of the United States, residing at Ridgefield Park,
in the county of Bergen and State of New Jersey,
have invented a new, original, and ornamental
Design for a Stair Tread, of which the
following is a specification, reference being had
to the accompanying drawing, forming part
thereof.

Figure 1 is a perspective view of a stair tread
showing my new design.

Figure 2 is a front edge elevational view there-
of, and

Figure 3 is an end elevational view thereof.

The dominant feature of my design resides in
the nosing portion of the tread.

I claim:

The ornamental design for a stair tread, as
shown and described.

THOMAS J. LEWIS.
